RAILWAY TRAFFIC CONTROLLING
APPARATUS

Herbert A. Wallace, Edgewood, Pa., assignor to
The Union Switch & Signal Company, Swiss-
vale, Pa., a corporation of Pennsylvania

Application September 17, 1941, Serial No. 411,163

3 Claims. (Cl. 246—34)

My invention relates to railway traffic controlling apparatus, and it has particular reference to the organization of such apparatus into railway signal systems for controlling traffic on a stretch of railway track. More particularly, my invention relates to signal systems for stretches of railway track divided by insulated joints into successive adjoining track sections and arranged and organized to provide protection against false indications due to a failure of the joints separating a section from the next adjacent section.

In railway signal systems, particularly those utilizing coded track circuit energy and arranged to govern traffic on a stretch over which traffic normally moves in but one direction, it is customary to supply the rails of each section at its exit end with track circuit current which is utilized to control a track relay connected to the rails adjacent the opposite or entrance end of the section, and the track relay is utilized to control the operation of an associated wayside signal and the supply of trackway energy to the rails of the next adjacent section in the rear. In such systems, the energy supplied to the exit end of a section might leak forwardly over the insulated joints in the event of a failure of the insulation of the joints separating such section from the section in advance, and this forwardly leaking current might falsely energize the relay of the advance section to cause the signal of such section to display a false indication. Various schemes have been proposed heretofore to protect against false energization of track relays due to the failure of insulated joints, but generally such systems necessitate the use of special relays for detecting current leaking past the insulated joints and for altering the character of the current supplied to the rear section when such leakage is detected.

An object of my present invention is to organize railway traffic controlling apparatus into railway signal systems incorporating novel and improved means for protecting against false signal indications in the event of a failure of the insulated joints dividing the signaled stretch into insulated sections.

Another object is to provide signal systems wherein the above-mentioned protection against false signal indications due to failures of insulated joints is attained with a minimum of expense and involving no special detecting relays to detect a leakage of current over the insulated joints.

Another object is to provide signal systems wherein broken-down insulation joint protection

is effected by providing each section with trackway current responsive means selectively and uniquely responsive to the characteristics of the current supplied to the associated section.

5 Another object is to effect broken-down insulation joint protection in signaling systems by at times utilizing differently characterized currents in each of two adjacent sections.

Another object is to effect broken-down insulation joint protection and approach control in signal systems by means responsive only to current having characteristics distinctively different from the characteristics of the current operating the track relays controlling the signals along the stretch.

10 Another object is to provide novel and improved signal systems incorporating an approach relay for obtaining approach control of signal functions and providing broken-down insulation joint protection.

Another object is to provide novel and improved signal systems wherein signals governing traffic on a stretch are selectively conditioned to govern traffic by track circuits incorporating track relays responsive only to the characteristics of current supplied to a section and coded in accordance with traffic conditions in advance, and such signals are rendered effective to govern traffic by approach control means involving a track circuit including a track relay responsive only to current supplied to the section in the rear of the signal.

Another object is to provide railway signal systems incorporating novel and improved approach control means.

40 In accordance with my present invention, the above-mentioned and other important objects and characteristic features of my invention which will become readily apparent from the following description, are attained by at times supplying the adjacent track sections of a stretch with distinctively characterized currents and by providing each section with trackway current responsive means arranged to be responsive only to certain characteristics of the current supplied to the associated section, whereby a failure of the joints separating two adjacent sections and leakage of current from one section over such joint into the adjacent section at such times cannot cause operation of the trackway current responsive means of the adjacent section due to the difference in characteristics between such current and the current to which such current responsive means responds. The adjacent sections of the stretch may be normally supplied

each with current having similar characteristics and the characteristics of the current supplied to a section may be altered upon the approach of a train. The means employed to effect approach control of the characteristics of the track circuit current supplied may be utilized also to render effective the signals governing traffic on the stretch.

My invention also resides in the organization and arrangement of railway traffic controlling apparatus into signaling systems wherein the above-mentioned objects or various combinations of such objects are attained. I shall describe one specific arrangement or form of apparatus embodying my invention, and shall then point out the novel features thereof in claims.

The accompanying drawing is a diagrammatic view illustrating one form of apparatus embodying my invention.

Referring to the drawing, the reference character **X** designates a stretch of railway track over which traffic normally operates in the east-bound direction as indicated by an associated arrow or from left to right as viewed in the drawing. The stretch **X** is divided by the usual insulated joints **2** into a plurality of successive adjoining track sections of which only one section, **D—E**, is shown complete in the drawing.

Each section of track is provided adjacent its entrance end with a signal, designated by the reference character **S** with a suffix corresponding to its location, for governing traffic operating over the stretch in the normal direction of traffic movement. These signals may be of any desired type, such as semaphore, searchlight, color light, position light, etc., but for the purposes of the present description the signals are assumed to be semaphore signals each having the usual signal mechanism and also having a signal lamp **SL** which normally is dark but which becomes approach energized in a manner to be explained presently. Each signal **S**, as shown, also controls an associated circuit controller comprising a movable contact member **6** operated by the associated signal mechanism into engagement with a contact **7** to form a circuit controlling contact **7—6** whenever the associated mechanism conditions the signal to display either its clear or its caution aspect, and which contact member **6** is operated by the signal mechanism out of engagement with contact **7** and into engagement with another contact **8** to form a contact **6—8** when the associated signal is conditioned to display its stop aspect. The functions of the contacts of the signal circuit controllers will be made clear presently.

Each section of track **X** is provided with a track circuit comprising means for supplying track circuit energy, preferably of train control (100 cycle) frequency, to the rails at the exit end of the section and a track relay, designated by the reference character **TR** with a suitably distinguishing suffix, arranged to respond to current received from the rails at the entrance end of the section. The current supplying means of section **D—E**, for example, comprises a track transformer **TTE**, a coding device, or transmitter **CTE**, and a suitable source of 100 cycle alternating current, such as a generator not shown but having its opposite terminals designated by the reference characters **BX** and **CX**. The coder **CTE** may be of any suitable type and as shown comprises a constantly energized winding operating a plurality of coding contact members each at a different code rate. As shown,

coder **CTE** is provided with a contact member **75** operated alternately to open and close a circuit controlling contact at a rate of 75 times per minute, another two contact members **180** each **5** operated to open and close a circuit controlling contact at a rate of 180 times per minute, another contact member **15** operated to open and close a circuit controlling contact at the rate of 15 times per minute, and a contact member **20** **10** operated alternately to open and close a circuit controlling contact at a rate of 20 times per minute. It is readily apparent that each contact member **180**, **75**, **15** and **20** of coder **CTE** when interposed in a circuit supplied with energy, is **15** effective to interrupt or code such energy at the rate of 180, 75, 15 and 20 times per minute, respectively. I shall hereinafter refer to the coding effected by contacts **180**, **75**, **15** and **20** of the code transmitter, as 180, 75, 15 and 20 code rates, respectively.

Transformer **TTE** has its secondary winding **12** constantly connected with the track rails at exit end **E** of section **D—E** and has its primary winding **13** supplied with 100 cycle alternating current normally coded at one or another of a plurality of code rates of a given order or class and coded at other times at one or another of a plurality of code rates of a distinctively different class. The code rates comprising the normal order of coding the current are selected so as to be ineffective to control the usual train-carried apparatus carried on trains traversing the stretch, and the distinctively different order of coding the current comprises the usual rates of coding effective to control the usual train-carried apparatus so that when the current is coded at such usual rate, it is effective to cause operation of train-carried apparatus and hence to establish control over the cab signal of a train in accordance with the code rate at which the current is supplied.

Specifically, the track circuit current supplying means of section **D—E** is arranged so that when approach relay **ARE**, hereinafter referred to, is picked up to close its front contact **31**, a secondary winding **13** of transformer **TTE** is connected to the source of alternating current through contact **20** or **15** of coder **CTE** according as contact **6—7** or **6—8** of the circuit controller associated with signal **SE** is closed. When, however, relay **ARE** is released and closes its back contact **32**, then winding **13** of transformer **TTE** is connected with the source of alternating current through contact **180** or **75** of coder **CTE** according as contact **6—1** or **6—8** of the circuit controller of signal **SE** is closed. It follows, therefore, that the current supplied to section **D—E** is coded at one or another of a plurality of relatively low code rates when relay **ARE** is picked up; is coded at one or another of a plurality of higher code rates when relay **ARE** is released; and that the particular code rate of each class is selected in accordance with the position of the signal **SE** associated with the section in advance. As shown, the circuit connection of the source to primary winding **13** of transformer **TTE** may be tuned, as by a condenser **26**, to resonance at a frequency corresponding to the frequency of current from the source indicated by the terminals **BX** and **CX**.

Relay **TRD** is energized by current received from the rails at the entrance end **D** of section **D—E** through the medium of a filter or tuning unit **TU—100**. The details of construction of unit **TU—100** are not shown in the drawing but

such unit usually comprises a reactor condenser tuning unit tuned to resonance at a frequency corresponding to the frequency of the current supplied from terminals BX and CX. In addition, if the track relay employed is a direct current relay, as shown, then the filter unit TU also includes a rectifier. Relay TRD accordingly is rendered selectively responsive to and is effectively energized only by current having a frequency corresponding to the frequency of current supplied from terminals BX and CX.

The track circuit apparatus of section D—E further comprises decoding apparatus selectively responsive to the relatively low rates of coding hereinbefore mentioned. Such apparatus may, for example, comprise a slow pick-up relay SPU, a plurality of slow releasing code registering relays CR one for each relatively low code rate, and a plurality of slow releasing code selecting relays CS. The slow releasing code registering relays CR are controlled by slow pick-up relay SPU and the slow releasing code selecting relays CS, and the slow acting characteristics of these latter relays are selected with respect to frequency of the 20 and 15 codes in such manner that which relay TRD responds to 20 code current, relay 20CR is energized, and when relay TRD responds to 15 code current, relay 15CR is energized. That is to say, current coded at the 20 code rate comprises "on" intervals of energy separated from each other by "off" intervals during which no energy is present, and which "on" intervals occur at the rate or frequency of some 20 times per minute, while 15 code current comprises alternate "on" and "off" intervals which occur at the rate of 15 times per minute. Relay 20CS is provided with an energizing circuit extending from terminal B through front contact 35 of relay TRD, back contact 36 of relay SPU and the winding of relay 20CS to terminal C, and when relay 20CS picks up, its front contacts 37 and 38 close to complete obvious energizing circuits for relays SPU and 15CS, respectively. When relay SPU picks up at the end of its slow pick-up period, relay 20CS is deenergized but is held in its energized position due to its slow releasing characteristics. The slow releasing characteristics of relay 20CS and the slow pick-up characteristics of relay SPU are selected so that the two intervals, taken successively, approximate just slightly less than the time required for a complete cycle of 20 code current. The slow release interval of relay 15CS is preferably of the order of one second, while relay 15CS energized over front contact 39 of relay 15CS, is likewise provided with a one second release interval.

When relay TRD responds to 20 code current, its front contact 35 is closed during the "on" interval of the code and is open during the "off" interval of the code, and this operation of relay TRD continues as long as 20 code current actuates the relay. When front contact 35 of relay TRD closes, relay 20CS becomes energized and picks up to pick up in turn relay 15CS, which relay in turn picks up relay 13CS. Relay 20CS also completes the circuit of relay SPU which picks up at the end of its slow pick-up interval to deenergize relay 20CS. Relay SPU remains up until front contact 35 of relay TRD opens and then relay SPU drops to close its back contact 36. As pointed out heretofore the slow acting intervals of relays 20CS and SPU taken together, approximate slightly less than a complete cycle interval of 20 code current, so that

relay 20CS releases during the "off" period of a cycle interval, to close its back contact 40, prior to relay TRD picking up due to the "on" interval of the next cycle period. Relays 15CS and 13CS, however, remain energized so that when relay TRD picks up due to the "on" interval of the next cycle period, relay 20CR is energized over a circuit extending from terminal B through front contact 35 of relay TRD, front contact 42 of relay 13CS, front contact 41 of relay 15CS, back contact 40 of relay 20CS, and the winding of relay 20CR to terminal C, and relay 20CR accordingly picks up. Relay 20CS also picks up, as pointed out previously, to open its back contact 40 and thereby deenergize relay 20CR, and close its front contact 37 to reenergize relay SPU. Relay 20CR is provided with a current impulse whenever relay TRD closes its front contact 35 due to an "on" period of the 20 code, and relay 20CR preferably is provided with slow releasing characteristics sufficient to maintain the relay armature in its attracted position between successive energizations of its winding due to 20 code. Relay 20CR therefore detects relay TRD following 20 code.

When relay TRD follows 15 code, both relays 20CS and 15CS drop, due to the length of the cycle period of the 15 code current, prior to relay TRD closing its front contact 35 when energized by each successive cycle period of 15 code current, and when front contact 35 closes, relay 15CR becomes energized over a circuit similar to the circuit of relay 20CR but including back contact 43 of relay 15CS and the winding of relay 15CR. Relay 15CS is supplied with an impulse of energy whenever relay TRD closes its front contact 35 in following 15 code current, and relay 15CR is proportioned to remain picked up between succeeding current impulses due to 15 code, thereby detecting relay TRD following 15 code.

Relays 20CR and 15CR associated with relay TRD cooperate to control the associated signal SD in such manner that when relay 20CR is picked up, signal SD is conditioned to display its clear aspect; when relay 20CR is released but relay 15CR is picked up, the signal is conditioned to display its caution aspect; and when both relays 20CR and 15CR are released, the signal is conditioned to display its stop aspect. It follows, therefore, that signal SD is selectively controlled by relays 20CR and 15CR in accordance with the code rate of operation of relay TRD.

My invention also incorporates means for obtaining an approach control or operation of a control function without using line wires by providing each section with a reversely fed auxiliary track circuit utilizing current having characteristics distinctively different from the character of the current utilized for controlling the track relay TR of the associated section. Such auxiliary track circuit may be provided by supplying to the rails at the entrance end of the section current having a frequency different from the frequency of the current supplied at the exit end; by providing at the exit end of the section an auxiliary track relay, designated by the reference character ATR with a suitably distinguishing suffix, arranged to be responsive only to the current supplied at the entrance end of the section, and by providing an approach control relay, designated by the reference character AR with a suitably distinguishing suffix, arranged to be energized through an associated decoding transformer AD, when the associated auxiliary

track relay operates in response to coded current received from the rails of the associated section. The auxiliary track circuit apparatus of section D—E, for example, comprises an auxiliary track transformer ATD having its secondary winding 27 connected to the rails at entrance end D and having its primary winding 28 connected through a contact 180 of coder CTD and a common connection, indicated by the reference character CC, to any suitable source of such distinctively differently characterized current, such as to a generator of current having a distinctive frequency, or as shown to a frequency changer FC comprising a full-wave rectifier 22 and a transformer 23. The input terminals of rectifier 22 are connected to the source of alternating current indicated by the terminals BX and CX, and the output terminals of the rectifier are connected to primary winding 24 inductively coupled with secondary winding 25 of transformer 23. As is readily apparent, rectifier 22 when energized by alternating current supplies to winding 24 of transformer 23 two pulses of unidirectional current in each cycle of alternating current, hence there is induced in secondary winding 25 of the transformer by these double frequency pulses of unidirectional current in winding 24, an electromotive force having a frequency which is double the frequency of the current supplied to rectifier 22. The terminals BX and CX may thus be regarded as a source of distinctively characterized current, having a frequency of, say, 100 cycles per second, and secondary winding 25 of frequency changer FC may be regarded as a source of current having a frequency of 200 cycles per second and thus having characteristics distinctively different from the 100 cycle current. The circuit connection of the source of 200 cycle current to the track rails is preferably tuned, as by a condenser 29, to effective resonance at the frequency of 200 cycles. It follows, therefore, that the rails at entrance end D of section D—E are supplied with 200 cycle current coded at the 180 code rate. At the opposite end E of the section, relay ATRE is connected through a filter unit TU—200, tuned to pass only current of 200 cycles, to the rails of section D—E and hence responds to the 200 cycle current to energize relay ARE through the medium of transformer AD when the associated section is unoccupied. Relay ARE not only governs the selection between the relatively low and relatively high code rates at which current is supplied to the exit end E of the section, as pointed out hereinbefore, but also controls an energizing circuit for lamp SL of signal SE in such manner that the lamp is illuminated when relay ARE is released to close its back contact 30 and the lamp is dark when relay ARE is picked up.

The other sections of track X are provided with track circuit apparatus substantially corresponding with the hereinbefore described apparatus of section D—E.

The rails of each of the sections of track X normally are supplied with 100 cycle current coded at the 20 or 15 code rate, over an obvious circuit including front contact 31 of the approach relay AR of the associated section, but when the approach relay AR is released, its back contact 32 closes and the associated section is supplied with 100 cycle current coded at the 75 or 180 code rate, as is readily apparent from an inspection of the drawing. The auxiliary track relay ATR of each section is controlled by 200

cycle current coded at the 180 code rate supplied to the entrance end of the associated section, so that when the associated section is unoccupied, relay ATRD operates to pick up the auxiliary track relay ARD to cause the associated section to be supplied with current coded at one or the other of the relatively slow code rates and hence condition the decoding apparatus associated with the main track relay TR of the associated section to be effective to control the associated signal.

When, however, a train enters the section, the auxiliary track relay ATR of such section is shunted and releases. Back contact 32 of the associated approach relay AR thereupon closes to shift the coding of the 100 cycle current supplied to such section from the relatively low code rates to the higher rates of coding, whereupon the train-carried apparatus on the train is caused to respond to such current. After the section becomes vacated, the approach relay AR of the section picks up and the coding of the track circuit current is restored to its normal low rates of coding.

It is readily apparent that in the event of a breakdown of the insulation of the joints separating two adjoining sections, the 100 cycle current might leak from the rear section into the advance section to falsely energize the TR track relay of such advance section, and the 200 cycle current might leak from the advance section into the rear section to falsely energize the auxiliary ATRD track relay of such rear section. Under such assumed conditions, the entrance of a train on a section might not cause the auxiliary track relay of such section to be released, hence the coding of the 100 cycle current supplied to the rails of such section would not be shifted from the relatively low code rates to the higher code rates. The train-carried apparatus on the train accordingly would not respond to such low code rates and would not indicate a proceed indication to the engineer of the train. When the train nears the exit end of the section, however, and shunts the rearwardly leaking current away from the auxiliary track relay, relay ATR then releases to shift the coding of the 100 cycle current from the relatively slow code rates to the more rapid code rates, thereby causing the track relay of the section in advance to operate at the more rapid code rate. The decoding apparatus associated with each track relay is of course non-responsive to trackway current coded at the relatively rapid code rates, hence the associated signal would be controlled to its stop indication if the associated section is occupied, and the associated signal would then select the proper rate of coding the 100 cycle current supplied to the rear section to that proper under the traffic conditions in advance. It follows, therefore, that the apparatus functions in the event of a failure of the insulated joints to provide protection against displaying false signal indications on a train traveling on the track by preventing the train-carried apparatus from being controlled by the trackway current until the current in the section is changed to a code rate effective to operate the train-carried apparatus but ineffective to operate the trackway decoding apparatus should this current leak forwardly over broken-down insulated joints.

Although I have herein shown and described only one form of railway traffic controlling apparatus embodying my invention, it is understood that various changes and modifications may be made therein within the scope of the ap-

pended claims without departing from the spirit and scope of my invention.

Having thus described my invention, what I claim is:

1. In combination with a section of railway track, a wayside signal at the entrance end of said section for governing traffic in one direction therein, trackway current supplying means for supplying current to the section at its exit end, wayside means receiving current from the rails at the entrance end of said section, decoding means operated by said wayside means and arranged to respond selectively to operation of said wayside means by current coded at one or another of a plurality of code rates of a given class but not of another class, means governed by said decoding means for selectively controlling said wayside signal, means normally effective for coding the current supplied to the section by said trackway current supplying means at one or another of said plurality of code rates of said given class and responsive to traffic in said section for shifting the coding of said current to one code rate or another of said other class.

2. In combination with a section of railway track, a wayside signal at the entrance end of said section for governing traffic in one direction therein, trackway current supplying means for supplying current to the section at its exit end, wayside means receiving current from the rails at the entrance end of said section, decoding means operated by said wayside means and arranged to respond selectively to operation of said wayside means by current coded at one or another of a plurality of code rates of a given class but not of another class, means governed by said decoding means for selectively controlling said wayside signal, coding means effective to

code current supplied to the section by said trackway current supplying means at one rate or another of said given class or said other class, and means for selecting the class of coding effected by said coding means, said means being controlled by current transmitted from a source at said one end of the section to the other wholly over a track circuit comprising the rails of said section.

3. In combination with a section of railway track, a wayside signal at the entrance end of said section for governing traffic in one direction therein, trackway current supplying means for supplying current having certain characteristics to the section at its exit end, wayside means receiving current from the rails at the entrance end of said section and arranged to be responsive only to the characteristics of the current supplied to the exit end of said section, decoding means operated by said wayside means and arranged to respond selectively to operation of said wayside means by current coded at one or another of a plurality of code rates of a given class but not of another class, means governed by said decoding means for selectively controlling said wayside signal, coding means effective to code current supplied to the section by said trackway current supplying means at one rate or another of said given class or said other class, and means for selecting the class of coding effected by said coding means, said means being controlled by current having characteristics distinctively different from the characteristics of current supplied by said trackway current supplying means and said distinctively characterized current being transmitted from a source at said one end of the section to the other wholly over a track circuit comprising the rails of the section.

HERBERT A. WALLACE.
